RADIO TUBE TAP

Milton Alden, Brockton, Mass.

Application May 11, 1937, Serial No. 141,919

6 Claims. (Cl. 173—269)

This invention relates to a socket device or female connector especially adapted to be placed upon the external metal caps with which radio tubes of the so-called screen grid type are provided.

More particularly my invention includes a connector of this type which can be used in connection with differing types of radio tubes, provided with such metal caps or plugs of various dimensions.

One purpose of my invention is to provide a connector for use with screen grid tubes which shall be insulated and prevent the accidental happening of short circuits by contact of other metal bodies therewith, and also to prevent the undesired connection of the operator's body to the cap when placing it upon the tube. It has often been found that such caps are removed from tubes or placed upon the same while the tube is in actual operation, as for example when a number of tubes are successively placed in a socket in order to determine their comparative operating qualities.

When an uninsulated grid cap is employed under these conditions, there frequently occurs the production of undesirable sounds from the radio receiver, or even the setting up of violent oscillations which may be dangerous to certain portions of the receiver, such as condensers.

Another purpose of my invention is to allow a tap-off to be made from the screen grid circuit of a radio tube without breaking its normal connection to the rest of the radio receiver.

Yet another purpose of this invention is to provide an insulated grid cap for use in connection with so-called "tube checkers", where it is desirable that such grid cap be capable of employment with tubes provided with different sized plugs for connection thereto.

Yet another object of this invention is to provide a grid cap in which means are provided so that when the cap is pressed down over the tube plug, the plug will be prevented from entering the cap beyond a certain point, so that the wire connecting to the cap may be firmly soldered to a point in the grid cap which is not reached by the plug on the tube.

Referring now to the drawing hereunto attached

Fig. 1 represents in cross section a double grid cap constructed according to my invention and shown in place over the plug end of a radio tube.

Fig. 2 represents in perspective an exploded view of my double grid cap, illustrating the manner in which the various parts are assembled.

Fig. 3 is a transverse sectional view of the device on the plane of the line 3—3 of Fig. 1 but without the wire.

My grid cap comprises a body portion 10, taking the form of a cylinder of large diameter 11 and a cylinder of relatively smaller diameter 12. These cylinders are concentrically connected with one another so as to form an elongated body.

For the purpose of imparting additional strength to the structure, or of allowing it to fit over a radio tube plug by pressing it still farther upon this plug, I may provide an enlarged collar 13 located at the outer extremity of the larger cylinder. These two cylinders have a partition wall 14 lying therebetween. This wall is pierced by a central aperture 15, which allows the passage therethrough of a hollow eyelet 16. This eyelet is provided with a central passageway 16'.

I provide a clip 17 of such size as conveniently to fit within the smaller cylinder and another clip 18 of such size as conveniently to fit within the larger cylinder. These clips are preferably constructed of springy sheet metal, having a generally U-shaped form. The legs of the U in each case are so spaced as to correspond with the diameter of the tube plug over which they are to be inserted and due to the springy nature of the material, each one of these clips will make satisfactory contact with tube plugs having differences of diameter as great as are encountered in practice. Thus, by the employment of two different sized clips, I am enabled to make connection with tube plug structures of a wide range of size. In the assembly of my device, the eyelet 16 is inserted through the aperture 19 in clip 17, through the aperture 15 in the body dividing wall and through the aperture 20 in clip 18.

Its smaller end may then be headed over by any convenient means, thus serving to form a compact and relatively rigid structure, where both clips have the bridge portions of their respective U's firmly held against the dividing wall 14 by means of the eyelet 16 which serves to rivet them in place.

For purposes of external connection to my plug cap I provide an aperture 21 located in a lateral portion of one of the cylinders, preferably the larger cylinder for purpose of more convenient assemblage. Through this aperture passes an insulated conductor 22. This conductor has the insulation removed from its end portion for a sufficient distance so that such bared portion will pass completely through the central passageway of eyelet 16 and may be sol-

dered or otherwise fastened upon the opposite end of this eyelet as indicated at 22'. Likewise I have found it desirable to solder or otherwise fasten this conductor to the eyelet at the point 23 where it enters the passageway of the eyelet. If desirable, for any reason, the entire passageway through the eyelet may be filled with solder to more securely hold the wire in position. The turning of the wire at the point where it leaves the eyelet, and its passage through aperture 21 serve to relieve the soldered joint from a portion of any strain which may be inserted upon the wire. The internal soldering of this wire may conveniently be done by means of a soldering iron having a relatively small point which can be inserted into the cylinders, constituting the insulating body of this cap. Undue rotation of the clips, which might loosen or break the wire connection, is avoided by providing the body recesses with shoulders 30, which act to confine the rotational motion of the clips to a few degrees, as shown in Fig. 3.

I have found that it is highly desirable for the connecting wire of my cap to be thoroughly insulated to a point extending within the body of the cap so that the insulation will not readily be pulled back and expose a portion of bare wire outside the cap, which contingency might allow an accidental short circuiting connection to occur where the wire was thus bared. However it is possible and sometimes preferable for my invention to have the clips and the eyelet assembled into the insulating body at the point of manufacture and then be supplied to the consumer in this condition, allowing him to insert his own connecting wire therein, as he may desire.

Besides the uses above pointed out of allowing the tube checker to be connected to screen grid tubes having various sized external plugs, my invention is also susceptible to many other uses. For example, a radio set may be provided with screen grid caps constructed according to my invention and thus be enabled to employ tubes of different types at will, in a single socket.

In case that it is desired to use my invention as a means of affording a tap-off to an existing circuit already derived from the tube plug, one convenient method of so doing is the following.

My grid cap is placed upon the tube plug structure and the connecting wire leaving the side of the cap will afford one circuit connection to this terminal of the tube. In the other end of my cap there may then be placed a conducting plug of sufficient length so that it will project beyond the insulating body of my cap. An additional circuit connection may then be made to this secondary projection by any suitable cap device, such as another cap built according to my invention. It can be seen that in this fashion a great number of circuits may be connected to a single tube plug terminal, if so desired, merely by placing a series of my cap devices one on top of the other, with suitable connecting plugs serving to key each cap to the next one, and each cap affording one external connection through its wire conductor.

The end 12 of the device serves as an extension handle to facilitate the use of the device when applying it to a tube tip which fits in the socket 18. Vice versa the end 13 serves as a handle for applying the device to a tip which fits in socket 17. When only one socket or clip is necessary the device may be closed at the opposite end. While I have referred to the body as

"cylindrical" it should be understood that this term is not used in its true geometrical sense as the cross section might be polygonal.

If desired the body and the conductor may be shielded.

I claim:

1. A tube tap having an insulating body with oppositely disposed recesses at the two ends thereof respectively, a spring clip in each recess, a hollow rivet connecting said clips and an insulated conductor entering laterally through the body and having an inner portion thereof parallel to the main axis of said body and soldered into the hollow rivet so as to minimize the effects of external pulling strain upon said inner portion of said conductor.

2. A double-ended grid cap in the form of two metallic clips connected to one another at substantially the center points of each clip so as to form a double U-shaped structure, by means of a hollow cylindrical body having an axially extending opening therethrough and being of a diameter small relative to the diameter of said clips, said cylindrical body affording entrance into the axial opening thereof for a connecting wire and said clips and said cylindrical body being enclosed by insulating material substantially at all points except the open ends of said clips and at a point affording entrance to said wire.

3. An insulated grid cap including a hollow body of insulating material provided with recesses of different sizes at its opposite ends, said recesses having a common bottom, constituting a division wall therebetween, connecting clips fitting into each respective recess, each clip corresponding in size to its respective holding recess, a hollow rivet passing through said clips and said common division wall so as to hold the clips firmly thereagainst, a connecting wire passing through a lateral wall of said insulating body, bending substantially at right angles and entering said hollow rivet with the portion thereof lying within said rivet bared and the portion thereof situated at the point of entrance into said insulating body covered with insulation, and means for fastening said wire within said rivet.

4. An insulated grid cap for radio tubes and the like including an insulating body in the form of two cylinders of unequal diameter joined to one another so as to form an elongated body, and having substantially at the point of juncture an insulating disc forming a partition therebetween, said partition being provided with a central aperture therethrough, a first metallic clip of the U-shaped type substantially conforming to the internal diameter of one cylinder, a second clip of like type and substantially conforming to the internal diameter of the second cylinder, both said clips being provided in their respective bridge portions with apertures substantially conforming in size with the central aperture in said partition, and lining up therewith when said clips are inserted in their respective cylinders, a hollow eyelet passing through said apertures in said clips and said partition so as to hold said clips against said partition, at least one of said cylinders being provided near its point of juncture with the other cylinder with a lateral aperture, whereby a connecting wire may be inserted laterally into said cylinder, so as to pass into said hollow eyelet.

5. A double connector including at the respective ends thereof, two clips of different diameters, a common mounting member lying therebetween,

connecting and fastening means passing through said mounting member and holding the bases of said clips upon said mounting member and respectively opposite one another so as to locate the open ends of said clips substantially 180° apart, said fastening means having a hollow passage extending therethrough longitudinally of the connector, insulating means covering both said clips except the open ends thereof and having a discrete aperture therein affording a lateral point of entry, a conductor extending through said discrete aperture laterally of the connector and having its innermost portion bent substantially at right angles to its lateral portion, and extending through said fastening means so as to extend axially of the connector.

6. A grid cap including an elongated one-piece insulating body having oppositely disposed

recesses with an insulating partition therebetween, said partition having a central aperture therethrough, two metallic U-shaped clips of different sizes, one lying within each recess of said body, each of said clips having an aperture in its respective bridge portion, coaxial with said central aperture of said insulating partition, a fastening member passing through said central aperture and the respective apertures of said clips so as to hold said clips against opposite sides of said insulating partition, said body being provided with a lateral aperture leading to one of said recesses, and a connecting wire passing through said lateral aperture and having its inner portion mechanically and electrically connected to one of said clips.

MILTON ALDEN.
